Primary Examiner — Ralf Seifert*(74) Attorney, Agent, or Firm* — Remark Law Group PLC(57) **CLAIM**

The ornamental design for a pulse damper, as shown and described.

DESCRIPTION

FIG. 1 is a top perspective view of a pulse damper showing our new design;

FIG. 2 is a bottom perspective view;

FIG. 3 is a front view;

FIG. 4 is a rear view;

FIG. 5 is a first side view;

FIG. 6 is a second side view;

FIG. 7 is a top view; and,

FIG. 8 is a bottom view.

Any portion of the pulse damper shown in broken lines is for the purpose of illustrating environmental structure and forms no part of the claimed design.
